BY *R. J. Whitaker*

his ATTORNEY

UNITED STATES PATENT OFFICE

CHARLES P. SMITH, OF TULSA, OKLAHOMA, ASSIGNOR TO BURST-WEBSTER ENGINEERING AND SALES COMPANY, OF ST. LOUIS, MISSOURI, A CORPORATION OF MISSOURI

POWDER DISPENSER

Application filed January 8, 1931. Serial No. 507,443.

An object of my invention is to provide a holder for powder which holder may eject powder onto a powder puff. Another object is to design a dispenser for face powder which is neat in appearance; compact, inexpensive, positive in action and durable. A still further and important object is to use a mechanism within the container which will prevent caking of the powder to be dispensed. Another object is to provide a powder dispenser which may be quickly refilled.

Other objects and advantages of my invention will be apparent from a reading of the following description, taken in connection with the drawing and pointed out in the subjoined claim.

In the drawing wherein the same part is designated by the same reference number.

Figure 1 is a perspective view of the powder dispenser.

Fig. 2 is a vertical longitudinal cross section.

Fig. 2A is a section on line A—A of Fig. 2, looking in the direction of the arrows.

Fig. 3 is a perspective of the disassembled dispensing device; and,

Fig. 4 is a perspective view of a modified form.

Number 5 indicates in general a substantially cylindrical member having cap 6 screw threaded at 7. The end of the cap opposite the threaded end has a central bore to snugly fit the cylindrical wall 5.

Cylinder 5 is slightly reduced in diameter and a cut away portion or slot 9, clearly shown in Fig. 3, permits introduction of the powder to be dispensed.

Figure 4 shows a modified form to admit powder. In this construction a sleeve 10 has an opening 11 to register with a similar aperture 12 in the cylinder. After powder is poured through openings 11 and 12 the sleeve 10 is turned. The mechanism for ejecting the powder is the same in both forms and this operates as follows:

Within one end of the cylinder 5 through bore 13 a rod 14 may be reciprocated. The rod 14 is reduced in diameter at shoulder 15.

Seated against shoulder 15 is a washer 16

perforated at 17, the washer being mounted on the shaft or rod 14.

To the other end of the rod 14, at the opposite end of the cylinder 5, is attached a member 18 which is in effect a piston. The piston is shown with a seat of 45°. Around the periphery of the piston and cut in the wall 19 of the cylinder are a plurality of grooves 20 clearly illustrated in Figs. 2A and 3.

Around rod 14 is a helical spring 21. It normally seats the piston 18 in the open end of the member 5. In addition to this function this spring has the important object of agitating the powder, keeping it from caking and forming a deposit on the inside wall of the cylinder 5. A button 22, having a chain ring or bail 23, is attached to the outer end of the rod 14. This button limits the movement of the rod 14 and the piston 18.

After powder has been inserted, as heretofore described, the button 22 is pressed. This compresses the spring 21, and pushes the piston 18 out. During this stroke the shoulder 15 abutting the washer 16 causes the spring 21 to loosen the powder. No powder is ejected on this stroke because the removal of the piston 18 causes a partial vacuum.

When the finger is released from the button 22, the spring 21 forces the piston 18 to seating position. During this stroke powder must leave the container if possible. Its only exit is via grooves 20. After the piston is seated powder cannot leak from the dispenser into the hand-bag or purse.

The device may be made of any material, inexpensive or high-priced, and if desired it may be hung on a chain by the ring 23. Other material than face powder may be inserted and ejected. With slight changes, using the same principles, a table salt-pepper shaker or dispenser could be made. Damp salt could easily be agitated and ejected.

While I have shown and described the preferred forms of my invention, it will be obvious that various changes in the details of construction and in the proportions may be resorted to for successfully carrying my invention into practice, without sacrificing any of the novel features or departing from the scope of the appended claim.

What I claim and desire to secure by Letters Patent of the United States is:

A face powder dispenser comprising a cylinder, means to fill the cylinder with powder to be ejected, a rod reciprocable in and extended through one end of said cylinder, a plunger and ring on the free end of said rod, a piston mounted on the other end of said rod, said piston reciprocable in an orifice in the outer end of the cylinder, grooves in said orifice, and a helical spring extending through the cylinder and around the rod, said spring having the dual function of agitating the powder to be ejected and of forcing the piston within the orifice and cylinder.

CHARLES P. SMITH.
